CLAIM

The ornamental design for a combined cabinet and speaker housing, as shown and described.

DESCRIPTION

FIG. 1 is a perspective view of a combined cabinet and speaker housing, showing my new design;

FIG. 2 is a side elevational view of the side directly opposite to that appearing on the left of FIG. 1;

FIG. 3 is a side elevational view of the side directly opposite to that appearing to the right of FIG. 1;

FIG. 4 is a bottom plan view thereof.
